UNITED STATES PATENT OFFICE.

JOHN SCHADE, OF HOLYOKE, MASSACHUSETTS, ASSIGNOR TO NATIONAL BLANK BOOK COMPANY, OF HOLYOKE, MASSACHUSETTS, A VOLUNTARY TRUST ASSOCIATION OF COPARTNERSHIP HAVING AS TRUSTEES F. B. TOWNE, E. S. TOWNE, J. M. TOWNE, AND F. W. WILSON.

LOCKING DEVICE FOR TELESCOPING ELEMENTS.

Application filed February 3, 1927. Serial No. 165,548.

This invention relates to locking means for flat telescoping elements, and has for its object to simplify and improve upon the construction shown and described in my Letters Patent No. 1,542,841, issued June 23, 1925.

Another object of the invention is to provide very simple and effective means of this description, not likely to get out of order 10 and readily applied for use.

Further objects of the invention will appear from the accompanying description supplemented by the drawings in which latter

15 Figure 1 is a plan view showing the invention applied to an ordinary loose leaf ledger—

Figure 2 is a section at the line 2—2 of Figure 1 with the sections locked—

20 Figure 3 is a section at the line 3—3 of Figure 2—

Figure 4 is a view similar to Figure 2 showing the sections unlocked—

25 Figure 5 is a section at the line 5—5 of Figure 4—

Figures 6 and 7 are sections at the line 6—6 of Figure 3, with the sections respectively locked and unlocked—

30 Figures 8 and 9 are broken views, similar to Figures 4 and 2, but showing modifications of the invention with the sections respectively unlocked and locked, and

35 Figure 10 is a detail broken sectional elevation on an enlarged scale similar to Figure 4 and showing the manner of supporting the spring.

Similar numerals of reference denote like parts in the several figures of the drawing.

40 While the invention is shown as applied to a loose leaf ledger, it is, of course, applicable to flat telescoping parts such as are used in various arts.

45 The parts of the loose leaf ledger will be briefly referred to without any detail description thereof since such parts are well known.

50 1, 2, are the usual metallic cheek pieces of the ledger, and to these cheek pieces are respectively secured throughout their length the plates 3, 4, having the usual rectangularly disposed bottom portions 5, 6, which overlap each other in sliding relation.

The outer extremities of these bottom por-

tions 5, 6, are bent upwardly at right angles so as to provide ends 7, 8, and terminate at their upper edges in inwardly extending flanges 9, 10, the latter underlying the former in telescoping relation, and these flanges are normally spaced apart for the purpose hereinafter to be explained.

The parts which have just been described form a part of the construction of an ordinary loose leaf ledger and no further description of the latter is deemed necessary.

This invention is applied to both ends of the loose leaf ledger construction, but the description will be limited to the application of the invention to only one end of such ledger, the other end of the ledger in all respects being a mere duplication.

Pivoted at 11 to the end 8 of the inner telescoping element is a locking dog 12, and pivoted respectively to a stud 13 carried by the lower outer end of said dog, and to a stud 14 carried by the end 8, are guide blocks 15, 16, from which extend respectively teats 17, 18, and these teats extend within the ends of a coil spring 19 whereby the latter is held against accidental displacement and is properly guided during the 75 swinging movements of the locking dog, as will be readily understood from Figure 10.

In the simplest and therefore the preferred form of the invention, as illustrated in the several figures of the drawing, except Figures 8 and 9, the pivotal point 13 on the dog will be carried above the pivotal point 11 of the dog itself, when the dog is swung to unlocking position, and therefore the spring will function to preserve this unlocking position of the dog, as illustrated particularly at Figure 4, but when the dog is swung to locking position this point 13 will be carried below the point 11 and the spring will then function to urge this dog into locking position, thereby increasing its bite in the manner presently to be explained.

Thus it will be seen that, in the preferred construction, the spring performs a double function.

The dog extends upwardly through an opening 20 formed by cutting away the flange 10, and terminates in any suitable operating finger piece 21 which extends above the flanges.

The outer edge of the dog is cut away to

form a gate 22 into which the flange 9 of the outer telescoping member normally extends, as shown at Figures 3 and 5, and when the dog is swung to unlocking position 5 this flange will be spaced from the walls of the gate 22 as shown at Figures 5 and 7, but when the dog is swung in the reverse direction to locking position these gate walls 10 will come in contact with this flange both at its upper and lower edges, the corner portions of these walls biting said edges, as shown at Figures 3 and 6, but this biting 15 will be accentuated by the action of the spring 19 which will then be positioned as shown at Figure 2, and any attempt to separate these telescoping sections will only tend to increase the bite of the dog against this flange 9.

Since the dog is pivoted to the end 8 of 20 the inner telescoping section the latter will be slightly raised when the walls of the gate 22 contact the flange 9, as is shown particularly in comparing the position of parts shown respectively at Figures 2 and 4, but 25 the flange 10 will never contact the flange 9, and the inner telescoping sections, when the parts are locked as above described, will be substantially in a floating condition within the outer telescoping element.

30 It is not necessary that this spring 19 should perform the double function above set forth, and therefore, referring particularly to Figures 8 and 9, studs 23 and 24 are so located respectively on the dog 12 and end 35 8 that the spring will only act to emphasize the locking position of the dog, and a plate spring 25, secured to a stud 26 carried by the plate 8, has leaves 27, 28, which bear respectively against the under side of the 40 flange 10 and against the flat seat 29 located on the dog 12, in order to hold the dog in unlocked position, as is shown at Figure 8.

When operating the dog to locking posi-

tion this spring 25 will be forced upwardly, and as soon as the stud 23 has passed below 45 the pivotal point 11 the coil spring will by its reaction force the lower end of the locking dog downwardly so as to increase the bite of the walls of the gate 22 against the flange 9.

50 While a coil spring has been shown and described for assisting the pivoted dog in functioning, it will be clear that any suitable form of spring element may be employed, the adaptation in the particular connection above described being a matter of mere mechanical skill.

55 What is claimed is:—

1. The herein-described means for locking together flat telescoping elements, comprising a locking member pivoted to the inner of said elements and having a gate within which the outer element extends and capable of being swung into locking engagement with the latter and also into unlocking position free of said outer element, and spring means for maintaining both positions of said member.

2. A locking means for flat elements that are normally spaced apart and telescope one 70 within the other, comprising a dog pivoted to the inner of said elements and having a laterally extending gate within which the outer element is housed, the walls of said gate at their corners biting the opposite 75 faces of said outer element when the dog is swung to locking position, and spring means for maintaining said locking position.

3. A construction as in claim 2 further distinguished in that the corners of the gate 80 bite the opposite faces of the outer element in staggered relation, and the telescoping elements are spaced apart when locked.

In testimony whereof I affix my signature hereto.

JOHN SCHADE.
